ATTORNEYS

UNITED STATES PATENT OFFICE.

ERNEST JORDAN, OF NEW YORK, N. Y.

AIR HEATER FOR FURNACES.

Application filed December 12, 1924. Serial No. 755,515.

To all whom it may concern:

Be it known that I, ERNEST JORDAN, a citizen of the United States, and a resident of the city of New York, Richmond Hill, 5 borough of Queens, in the county of Queens and State of New York, have invented a new and Improved Air Heater for Furnaces, of which the following is a full, clear, and exact description.

10 This invention relates to air heaters for furnaces and has for an object to provide an improved construction wherein not only heated air may be readily provided above the bed of coals in the furnace but the volume may be regulated.

15 Another object of the invention is to provide an attachment for furnaces which may be connected with the furnace door and which will supply heated air above the bed of coals in the furnace.

20 A further object, more specifically, is to provide a device for supplying heated air to furnaces wherein there is substantially no loss of heat units in heating the air previous to its entrance into the furnace.

25 In the accompanying drawing—

Figure 1 is a perspective view of an air heater embodying the invention, the same being shown applied to a furnace door.

30 Figure 2 is an elevation of one end of the heater shown in Figure 1, the same being on an enlarged scale.

Figure 3 is a sectional view through Figure 2, on line 3—3.

35 Fig. 4 is a fragmentary sectional view through Figure 3 on line 4—4.

Figure 5 is a sectional view through Figure 3 on line 5—5.

40 In heating furnaces and particularly the usual heating furnaces in dwellings, coal is used as the fuel. In order for the coal to burn properly, a proper draught must be provided and, consequently, much of the valuable fuel is driven off as gas before the 45 same becomes highly heated or before the same becomes consumed. To obviate this loss, numerous devices have been provided for supplying air to mix with this gas whereby it may become combustible.

50 In the present invention, an improved structure is disclosed in the accompanying drawing wherein heated air is supplied a short distance above the bed of coals and the air is heated to substantially the same 55 temperature as the gas whereby there will be produced a chemical affinity between the

gas and the air resulting in the ignition of the gas and a long flame. In order to accomplish this result without depriving the furnace of any heat units, the heater is connected to a furnace door 1, which door is provided with the usual sliding shutter or damper 2 and with a foraminous plate 3. All of the openings in the plate 3 are closed with fire clay, asbestos or other material 60 except the group within the base 4. The base 4 is provided with a circumferential flange 5 adapted to fit flatwise against the plate 3 and be bolted or otherwise rigidly secured thereto by the various bolts 6 acting on the angle clamps 7. By this construction and arrangement, the device may be readily applied or removed at any time without injuring any part of the furnace.

The base 4, together with part of the plate 75 3, forms an intake chamber 8 which receives air through the various openings 9 and through the openings of the shutter 2. The base 4 merges into a forwardly extending body 10 which has passage-ways extending 80 therethrough hereinafter fully described, said passage-ways being in free communication with chamber 8 whereby the air is led out over the bed of coals 11 and finally discharged out the opening 12. The body 10 is provided with a deflecting loop or projection 13 whereby the heated air is deflected 85 downwardly and is thereby caused to mix more readily with the hot gases as they rise from the bed of coals 11.

90 In forming the device, the same is preferably formed into two parts, namely, the upper part 14 and the lower part 15. These parts may be formed in any desired manner but for the sake of cheapness are preferably cast. The upper part 14 merges in the upper part of the base 4, said upper part 14 having a flat plate as shown in Figure 1 and with an aperture 16 extending longitudinally thereof from the base 4 to point 17. The part 15 merges into the lower part of base 4 and presents a pair of channels or passage-ways 18 and 19 which open into the chamber 8. These passage-ways or channels merge into a front chamber 20 from 95 which the heated air is discharged out the opening 12 which is in the form of a slit as shown in Figure 4. In order to cause the air to travel from chamber 8 to chamber 20 in thin sheets, depending webs or flanges 100 21 and 22 extend downwardly from the plate 23 forming part of the structure 14.

As indicated in Figures 2 and 5, the positioning of the flanges 21 and 22 as just described, causes substantially V-shaped passage-ways to be presented or rather converge the passage-ways 18 and 19 into V-shaped openings through which the air passes from chamber 8 to chamber 20. As all parts of the device are heated by the flame from the bed of coals 11, the side walls of members 18 and 19, the plates 23 and flanges 21 and 22, all produce a heating action on the air as it moves toward the discharge opening 12. As all of the heat used in heating the devices and also in heating the air is returned to a position above the bed of coals by the discharge of the air through opening 12, none of the heat units are lost but, on the contrary, the gases rising from the bed of coals will become ignited as the heated air mixes therewith. In this way, a maximum number of heat units are secured from a given quantity of coal and all of the heat units are used in causing the furnace to function in the usual manner.

What I claim is:

1. In an air heater for furnaces, a body formed with a pair of substantially V-shaped members presenting passage-ways extending to near the center of the furnace, and a plate covering said passage-ways, said plate being provided with a depending flange extending centrally into each of the passage-ways for dividing each passage-way into substantially two parts, said plate overlapping said V-shaped member at the inner end for deflecting air from said passage-ways downwardly.
2. An air heater for furnaces, comprising a base formed into upper and lower parts, the upper part comprising a base section, a

plate extending substantially at right angles therefrom having a longitudinal slit for part of its length, an overhanging lip at one end, and a pair of parallel depending flanges, the other of said parts being provided with a pair of substantially V-shaped passage-ways accommodating said flanges, and a base section co-acting with the first mentioned base section for forming an intake air chamber and a bolt extending through said slit engaging said upper and lower parts for clamping said parts together at any point along the slit.

3. An air heater for furnaces, comprising an upper and lower part, said upper part being formed with a base section presenting part of a chamber and a bolt receiving flange, said upper part being also provided with a plate having a longitudinal slit therein and a depending outer end, the lower part being formed with a base section co-acting with the base section in the upper part for forming an air reception chamber, means extending from the last mentioned base section forming parallel V-shaped passage-ways, each of said passage-ways having a notch at the outer end, said upper plate fitting flatwise against said members and formed with longitudinally positioned flanges projecting into said members for substantially dividing the passage-ways therein so as to reduce the volume of air passing therefrom whereby more heat units in proportion may be absorbed by the air as it passes through the passage-ways and is finally deflected by said depending portion, and a bolt fitting against said members and extending through said slit for clamping said upper and lower parts together.

ERNEST JORDAN.
